UNITED STATES PATENT OFFICE.

LUKE C. OBER, OF BOSTON, MASSACHUSETTS.

IMPROVEMENT IN LANTERNS.

Specification forming part of Letters Patent No. 35,835, dated July 8, 1862.

To all whom it may concern:

Be it known that I, LUKE C. OBER, of Boston, in the county of Suffolk and State of Massachusetts, have invented a new and useful Improvement in Lanterns whose lamps are intended to produce light by the inflammation of kerosene or other hydrocarbon liquid rich in carbon; and I do hereby declare the same to be fully described in the following specification, and illustrated in the accompanying drawings, of which—

Figure 1 denotes an elevation, and Fig. 2 a longitudinal section, of my improved lantern.

In carrying out my invention I dispense with the ordinary chimney, and so construct the glass casing as to serve both as a chimney and as a casing to the lantern.

The nature of my invention consists in the arrangement of an india-rubber packing between the deflector-supporter and casing, whereby a tight connection is formed, so as to prevent any currents of air from passing upward between the said supporter and casing, such currents being caused to flow into the deflector and pass upward through and around it, as hereinafter set forth.

In the drawings, A denotes the lamp, and B the glass lantern-case.

C denotes the lower metallic portion of the lantern, whose sides are formed foraminous.

The lamp is such as is in common use for burning coal-oil—that is, it is provided with a wick-tube, D, wick E, and wick-elevator F, a foraminous deflector-supporter, G, and a deflector, H. On the upper portion of the deflector-supporter I form a wide annular flange, a, which I extend horizontally, and cover the same with india-rubber or other suitable elastic material, d.

The object of making the packing or connection elastic is to maintain a perfectly tight joint under any expansion of the metallic supporter, as well as to prevent any breakage of the glass portion by an expansion of the metallic portion.

The glass casing of the lantern is affixed to the cap g, which is united to the lower portion of the lantern in the ordinary manner. Moreover, the said casing, near its lower part, is formed with a contraction or neck, b, the part c, or that portion intended to rest upon the packing d, being formed flaring, as seen in the drawings. Such part c, when in place resting upon the india-rubber packing, serves to prevent the currents of air from passing up around the outer edges of the supporter, whereby all the air passing upward is concentrated and made to pass into the deflector, the greater portion passing upward through the same, while a smaller portion escapes through the orifices formed transversely through the lower part of the deflector and flows upward around the external surface thereof, whereby the flame is properly supplied with oxygen.

f f f, &c., denote metallic wires or guard-bars having their lower ends fastened in the screw-cap g, while their upper ends are affixed in a metallic cap or flange, I, extending around and supporting the upper part of the glass casing B. K is a conical guard or heat-deflector, which serves to deflect the heat of the lamp from the hand of a person, while L is the handle or bail, which is attached to the metallic cap I, as seen in the drawings.

Having described my invention, what I claim, and desire to secure by Letters Patent, is—

The arrangement of india-rubber or other elastic packing between the deflector-supporter and the glass casing of the lantern, whereby the currents of air are prevented from passing up between the said supporter and the casing and are caused to flow into the deflector and through and around the outer surface thereof, substantially in manner and for the purpose set forth.

LUKE C. OBER.
